UNITED STATES PATENT OFFICE

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY

LASTING MACHINE

Application filed June 8, 1931. Serial No. 542,851.

This invention relates to lasting machines having means for shaping an upper over a last and for driving fastenings to fasten the upper to a sole or insole (hereinafter frequently referred to as the sole). The invention is herein illustrated as applied to a machine in which the upper is pulled over the last successively in different locations as the shoe is presented in different positions by the operator, and in which the upper is fastened by staples the legs of which are curved by engaging them prior to and during their entrance into the shoe to anchor them in the shoe, as disclosed in Letters Patent 1,815,295, granted upon an earlier application of mine on July 21, 1931. It is to be understood, however, that in various novel aspects the invention is not limited to machines of that particular character.

An object of the invention is to provide a machine having not only means for driving fastenings to fasten the upper to the sole, but also means for laying the marginal portion of the upper inwardly over the sole and pressing it upon the sole in lasting the shoe without driven fastenings, as when cement is used to fasten the upper in lasted position. It is sometimes desired, for example, to last the shank portion of a shoe with staples driven and anchored as above described, and to last the sides of the forepart of the shoe with cement instead of with staples. In accordance with a feature of this invention the machine herein shown is so constructed as to adapt it to be readily used for these different purposes, the machine including in its organization an overlaying member which is movable at the will of the operator into such relation to the stapling mechanism as to move with the latter inwardly over the shoe bottom to lay the marginal portion of the upper over the sole and to press it upon the sole in lasting the shoe with cement instead of with staples. Novel means, moreover, is provided for moving this member quickly into or out of position for use on the shoe, and also novel means for interrupting the stapling operation when the member is in use. The machine illustrated has, in addition to a staple driver, means for feeding

staple wire and for forming staples; and to interrupt the stapling operation there is provided means for stopping the feeding of the wire and also for stopping the operative movement of the driver, thus preventing not only the driving of staples but also unnecessary wear of the parts. Conveniently the arrangement shown is such that by use of a single controlling member the operator can set the machine either to last the shoe with staples or to lay the upper over the sole while the wire-feeding means and the staple driver are idle. To render the driver inoperative the machine has novel means which prevents it from being retracted and prevents the tensioning of its operating spring.

Further features of the invention relate to means for controlling the shoe in the lasting operation. Machines of the type illustrated are provided with a shoe bottom rest and a side gage for controlling the shoe as the latter is presented by the operator in different positions during the progressive lasting of the shoe, the side gage being arranged to engage the side of the shoe near the edge of the shoe bottom. Since the above-mentioned overlaying member, when in use, is in such a position as to lie between the stapling mechanism and the bottom of the shoe, it is desirable that the shoe bottom rest be correspondingly lowered at that time, so that the bottom of the shoe may be presented in such relation to the overlaying member as to obtain the best results in lasting with cement. The machine is accordingly provided with novel means for adjusting the bottom rest, the construction shown comprising mechanism whereby the operator is enabled to effect a quick adjustment of it into different positions for lasting with staples and with cement respectively. The machine is further provided with means for effecting a quick adjustment of the side gage heightwise of the shoe, this adjustment, as illustrated, being effected by the same means that moves the overlaying member into and out of position for use on the shoe. In this manner the side gage is positioned as high as is necessary for good results in lasting with staples along the shank portion of the shoe bottom,

and when the overlaying member is in use at the forepart is so positioned as not to interfere with this member, as more particularly hereinafter explained.

5 The above and further features of the invention, including various novel details of construction and combinations of parts, will now be more particularly described by reference to the accompanying drawings and 10 pointed out in the claims.

In the drawings,

Fig. 1 is a view in front elevation of a portion of the head of a machine in which the invention is embodied;

15 Fig. 2 is a view of a portion of the structure in side elevation, showing the parts in the positions that they occupy in laying the marginal portion of an upper over an insole in lasting the shoe with cement instead of 20 with staples;

Fig. 3 is a section on the line III—III of Fig. 2;

Fig. 4 is a section partly on the line IV—IV of Fig. 2 and partly in a lower plane;

25 Fig. 5 is a view of a portion of the machine in side elevation, showing the parts in the positions that they occupy in laying the marginal portion of the upper over the insole and fastening it by a staple;

30 Fig. 6 is a section partly on the line VI—VI of Fig. 5 and partly in a lower plane;

Fig. 7 is a section on the line VII—VII of Fig. 5, showing portions of the staple-forming mechanism;

35 Fig. 8 is a plan view of a portion of the structure shown in Fig. 1; and

Fig. 9 is a perspective view of a portion of the means for adjusting the shoe bottom rest.

40 Since the invention is herein illustrated as applied to a machine of the same type as disclosed in the above-mentioned Letters Patent, only such features of the general organization as it is necessary to refer to for an 45 understanding of the invention will be mentioned in detail and these features will be described only in brief terms.

It will be understood that the shoe on its last is supported in the hands of the operator 50 and is presented successively in different positions in the progressive lasting of its opposite sides. To assist in determining the proper relation of the shoe to the lasting instrumentalities the machine is provided with 55 a side gage 10 arranged to engage the side of the shoe at or near the edge of the insole and with a shoe bottom rest 12 arranged to engage the outer face of the insole. The upper is pulled over the last and the insole when 60 the shoe is in each lasting position by a gripper comprising a pair of co-operating jaws 14. For laying the marginal portion of the upper inwardly over the insole and fastening it with staples there is provided a slide or 65 carrier 16 (Fig. 5) operated by a cam (not

shown) and movable along a guideway 18 in a forwardly and downwardly inclined direction toward the bottom of the shoe. This slide carries a staple guide or nozzle 20, a staple driver 22 and a deflector 24 which 70 engages the legs of the staples 8 and curves them prior to and during their entrance into the shoe so that they are anchored in the insole without necessarily emerging from its inner face, as illustrated in Fig. 5. The operative movement of the driver is in a rearward direction, and the deflector curves the legs of the staple forwardly away from the rear edge of the insole. It will be understood that in the forward movement of the 80 slide 16 prior to the driving of the staple the nozzle 20 and the deflector 24 lay the upper over the outer face of the insole.

The staple driver 22 is fastened to a driver slide 26 which is movable in a guideway 85 formed in a bracket 28 secured to a forward extension of the slide 16. The driver slide 26 is operated by a lever 30 which is pivoted on a stud 32 on the forward extension of the slide 16 and carries a lug 34 extending into a 90 recess in the driver slide. The lever 30 is operated by a bell-crank lever 36 which is pivoted on a rod 38 on the slide 16 and is operated, in turn, by a torsion spring 40 (Fig. 1). A forwardly extending arm of the bell-crank lever 36 carries a roll 42 which operates in a cam slot 44 in the lever 30, the cam slot being so formed that staple-driving movement is imparted to the lever 30 by upward movement of this arm. For swinging the 100 bell-crank lever 36 against the resistance of its spring 40 to retract the driver 22 and to tension the spring there is pivoted at 46 on the head of the machine a lever 48 on which is pivotally mounted at 50 a latch 52 arranged to engage the lower end of a plate 54 fast on a downwardly extending arm of the bell-crank lever 36. A spring 56 connected to the latch 52 and to a pin on the lever 48 holds the latch in engagement with the plate 54 when the slide 16 and the parts carried thereby are in their initial positions. When the slide is moved forwardly toward the shoe the latch 52 acts to swing the bell-crank lever 36 against the resistance of its spring 40 in response to 110 such forward movement, thereby retracting the staple driver 22 as the latter is being carried bodily forward by the slide. For operating the latch 52 to release the lever 36 and thus to cause the operation of the driver the slide 16 carries a screw 58 the head of which is arranged to engage a shoulder on the latch, as illustrated in Fig. 5. The forward movement of the slide 16, however, does not carry the screw far enough to release the lever 36, such release being effected in response to a swinging movement of the latch-carrying lever 48 effected by a cam (not shown) after the slide 16 has completed its forward movement. It will be understood 120 130

that by reason of such movement of the lever 48 the screw 58 causes the latch 52 to swing far enough to disconnect it from the plate 54. In the return of the parts to starting positions the latch 52 is held by a shoulder 60 on the lever 48 in position to connect again with the plate 54 when the slide 16 arrives at the end of its retractive movement.

The machine is also provided with means for forming a staple in response to the forward movement of the slide 16 and for transferring the staple from forming position into alignment with the driver. For this purpose the slide 16 carries an inside former 62 (Fig. 7) arranged to cooperate with a stationary outside former 64. Wire for forming the staples is fed automatically into position to be operated upon by the inside and outside formers through a nozzle 66 which is carried by the slide 16, this nozzle cooperating with a stationary shearing plate 68 to cut the wire. After the staple has been formed it is transferred downwardly into the path of movement of the driver by a transferring member 70 which operates between the inside and outside formers, this member being carried by a slide 72 (Fig. 5) movable in a guideway provided on the slide 16 and operated at the proper time by mechanism including a link 74.

The means for feeding the staple wire is substantially like that shown and described in Letters Patent No. 1,796,451, granted upon an application of mine on March 17, 1931. The wire is mounted on a reel 76 (Fig. 1) and is operated upon by feed rolls 78 and 80 from which it is conducted through a flexible tube 82 to the nozzle 66. The feed roll 78 is operated by pawl and ratchet mechanism through a link 84 and a bell-crank lever 86 provided with a roll 88 engaged by a cam 90. In order to stop the feed of the wire, when desired, there is provided a hand lever 92 having thereon a projection 94 arranged to engage a face 96 on the lever 86 and thus to hold this lever in such a position as to prevent it from being operated by the cam 90.

The machine as thus far described is constructed substantially as heretofore. For purposes of this invention there is provided means that may be utilized, when desired, to lay the marginal portion of the upper inwardly over the insole in lasting the shoe without staples, as when cement is used to fasten the upper to the insole. This means comprises an overlaying member 98 supported on the slide or carrier 16 and movable at the will of the operator into a position directly under the staple guide or nozzle 20 and the deflector 24 for engaging the upper and laying it over and upon the outer face of the insole while moving with the guide and deflector inwardly over and toward the shoe bottom, as illustrated in Fig. 2, or into a retracted position to permit the lasting of

the shoe with staples, as illustrated in Fig. 5. The member 98 is so formed as to engage the upper over a greater extent lengthwise of the edge of the shoe bottom than the staple guide and deflector, as is desirable in pressing the upper into position to adhere to the insole. The member 98 is secured to a slide 100 mounted in a guideway formed partly in a bracket 102 fast on the slide 16 and partly in another bracket 104 which is adjustably secured to the bracket 102 by screws 106. The slide 100 is controlled by a cam plate 108 which is pivoted on a stud 110 on the bracket 104 and is provided with a curved cam slot 112 (Figs. 4 and 6) in which lies a stud 114 carried by the slide. By swinging the cam plate 108 about the stud 110 the member 98 may therefore be moved either forwardly to a position under the staple nozzle 20 and the deflector 24, as illustrated in Figs. 2 and 4, or rearwardly to an idle position, as illustrated in Figs. 5 and 6. The cam slot 112 is so shaped at its right hand end (Figs. 4 and 6) as to lock the slide 100 against rearward movement in response to pressure of the shoe 90 on the member 98 when the member is in its operative position as shown in Fig. 4. A spring 116 bearing at one end on the bracket 104 and at its other end on the stud 114 serves to hold the slide 100 and the member 98 in retracted position (Fig. 6).

When the member 98 is in position for use the hand lever 92 is swung into position to interrupt the feeding of the staple wire, so that no staple will be formed; and conveniently this hand lever is utilized also to control the cam plate 108. For this purpose there is pivotally connected to the cam plate a rod 118 having adjustably fastened thereon a pair of collars 120 (Fig. 8) arranged to serve as abutments 105 engaged by a stud 122 through which the rod 118 extends, the stud being pivotally mounted on the lever 92. When this lever, therefore, is moved into position to stop the feeding of staple wire, as illustrated in Fig. 110 1, the plate 108 is swung to the left (Fig. 4) to position the member 98 under the staple nozzle and deflector for use on the shoe, and when the lever is moved into position to permit feeding of the wire the member 98 is 115 retracted to its idle position (Fig. 6). It will be understood that the connection between the rod 118 and the plate 108 is loose enough to permit such swinging of the rod as results from movement of the lever 92; 120 and the rod is loose enough in its bearing in the stud 122 to permit the short swinging movements that it receives in response to the reciprocating movements of the slide 16.

In order to avoid unnecessary wear as 125 well as noise in the operation of the machine, there is further provided means for rendering inoperative the mechanism that operates the staple driver 22 when the overlaying member 98 is in use. For this pur-

pose the slide 100 carries an arm 124 connected by a link 126 to one arm of a bell-crank lever 128 which is mounted on an extension of the bracket 104, the other arm of this lever being provided with means for connecting it to a screw 130 on the latch 52. This means comprises a split sleeve 132 and an arm 134 adjustably clamped in the sleeve by a screw 136, this arm having a slot into which the screw 130 extends. These parts are so arranged that when the member 98 is in its retracted or inoperative position, as illustrated in Fig. 5, the latch 52, by reason of the slot in the arm 134, is permitted to move as required to connect it to the plate 54 and to disconnect it therefrom and thus to cause the staple driver 22 to perform its staple-driving operations. When, however, the member 98 is advanced to its operative position under the nozzle 20 and the deflector 24 the arm 124 acts through the link 126 to swing the bell-crank lever 128 to such a position that the latch 52 is prevented by the arm 134 from swinging upwardly far enough to connect it to the plate 54 when the slide 16 is retracted from the shoe. Under these conditions the mechanism that operates the staple driver is unaffected by the reciprocatory movements of the slide 16 and the driver is not retracted nor is its operating spring 40 put under tension by the movement of the slide.

By reference to Fig. 5 it will be evident that in the operation of the machine along the shank portion of the shoe bottom the side gage 10, because of the inward curvature of the side of the last, can engage the shoe only in a location substantially opposite the edge of the insole, and that it must accordingly be positioned high enough, while engaging the shoe in that location, to permit the bottom of the shoe to be presented in proper angular relation to the direction of the forward movement of the stapling mechanism over the shoe. These conditions may render it advisable to position the gage, as illustrated, at such a height that its shoe-engaging end is in line with the overlaying member 98 and must therefore be lowered before that member can be used. In operating at the sides of the forepart, on the other hand, the shape of the last does not necessitate that the gage contact with the shoe directly opposite the edge of the insole. Furthermore, the fact that the member 98, when in use, is below the staple nozzle, and therefore necessitates a somewhat lower position of the side of the shoe than when lasting with staples, renders it desirable that the gage 10 also shall occupy a somewhat lower position at that time. In view of these considerations, the machine is further provided with novel means for adjusting the side gage 10 heightwise of the shoe into different positions for lasting the shoe with staples and with cement

respectively, the construction shown being such that the gage is controlled by the mechanism hereinbefore described for moving the overlaying member 98 into and out of position for use on the shoe. For the purpose in view the gage is pivoted on a stud 138 on a bracket 140 fast on the head of the machine and is acted upon by a torsion spring 142 which tends to swing its shoe-engaging end upwardly. At its rear end the gage is provided with a slot 144 through which extends a screw 146 threaded in the bracket 140. Slidingly mounted in a recess formed in a plate 147 attached to the bracket 140 is a rod 148 which extends under the rear end of the gage and limits swinging movement of the gage in response to the action of the spring 142, this rod being shaped to serve as a cam member for controlling the gage and being reduced in thickness at 150 to permit the shoe-engaging end of the gage to be elevated higher when the rod is in one position than when it is in another position. For controlling the rod 148 it is connected to the hand lever 92 which also controls the rod 118 as hereinbefore described, the rod 148 extending through a recess in the stud 122 and having fast thereon collars 152 arranged to be engaged by the stud. It will accordingly be understood that when the hand lever 92 is swung to the left (Fig. 1) to advance the overlaying member 98 into position for use and to render the staple-driving and wire-feeding mechanisms inoperative, the rod 148 is operated to lower the shoe-engaging end of the gage 10 (Fig. 2), and that when the lever is moved to the right to withdraw the member 98 to its inoperative position and to render the staple-driving and wire-feeding mechanisms operative, the rod 148 is moved to a position such as to permit the gage 10 to be swung farther upwardly by its spring 142 (Fig. 5). The plate 147 is hung on the stud 138 and has a slot 153 through which the screw 146 extends, the plate being adjustable about the stud 138 to vary preliminarily the height of the gage 10. A portion of the screw 146 extending through the slot 144 is arranged to clamp the plate 147 in adjusted position.

In view of the fact that the overlaying member 98 in its operative position is below the staple nozzle, as hereinbefore explained, and in order that the bottom of the shoe may be so inclined as to render this member, in that position, effective to press the marginal portion of the upper upon the insole over a substantial area widthwise of the shoe, there is further provided means for effecting a quick adjustment of the shoe bottom rest 12 heightwise of the shoe, so that its shoe-engaging end may be positioned at a lower level in lasting the shoe with cement than in lasting with staples. For the purpose in view the rest 12 is mounted in a holder 154 which is

provided with a sleeve portion 156 mounted for turning movement in a bearing in a fixed bracket 158 on the head of the machine. A screw 160 is threaded in the sleeve 156 and 5 bears against the member 12 to clamp it adjustably in its holder 154. To hold the sleeve 156 in its bearing there is provided a washer 162 overlapping a portion of the bracket 158, and a nut 164 which is threaded on the screw 10 160 and holds the washer against the bracket. By swinging movement of the holder 154 about the axis of the sleeve 156 the lower end of the shoe rest 12 is lowered or raised 15 for use in lasting the shoe with cement or with staples respectively, as indicated by full and dotted lines in Fig. 2. For swinging the holder to its different positions there is provided an eccentric 166 which is mounted in a recess in the holder and is fast on a rock 20 shaft 168 mounted in bearings in the bracket 158, this rock shaft having fast on its outer end a small lever arm 170 for turning it. For limiting the turning movement of the rock shaft 168 in the direction to raise the 25 lower end of the shoe rest 12 there is provided a shoulder 172 on the hub of the arm 170 which is arranged to engage a shoulder 174 on the bracket 158. To limit the turning movement of the rock shaft in the opposite 30 direction there is fast on the shaft, within a recess in the bracket 158, a collar 176 having a lower flat face 178 arranged to engage a corresponding face on the bracket 158 when the arm 170 has been swung a predetermined distance. The shape of the collar 176 is such as 35 not to interfere with the movement of the arm 170 in the direction to swing the shoe rest upwardly. The collar 176 is split and is clamped on the rock shaft 168 by a screw 180, so that the collar may be adjusted to 40 determine different limits of downward movement of the shoe rest. It will be understood that by means of the lever arm 170 the operator is enabled to move the shoe rest 12 quickly 45 into one or the other of its predetermined positions before or after movement of the lever 92 to render the overlaying member 98 operative or inoperative in the manner hereinbefore explained. By loosening the clamp 50 screw 160 the operator may release the member 12 and may then set it preliminarily at different heights as may be required by different operating conditions. It will be understood that when the shoe rest has been 55 adjusted by movement of the arm 170 it will be held in adjusted position by the eccentric 166, the friction between the different parts being sufficient to prevent any accidental displacement of the arm 170 and the rock shaft 168 60 after the adjustment.

From the foregoing description it will be evident that the invention provides a machine which may be quickly set either to last a shoe with staples or to lay the marginal portion of the upper over and press it upon

the outer face of the insole in lasting the shoe without staples, as by the use of cement. While it is contemplated, as hereinbefore suggested, that such a machine will be especially useful in lasting shoes in which the upper is fastened to the shank portion of the insole by staples and along the sides of the forepart by cement, it will be understood that the machine is not limited to this particular use, but is adapted to last shoes either with or without staples regardless of the particular portions of a shoe upon which either of these operations is performed. It will further be understood that while the machine herein shown is so constructed as to fasten the upper with staples, the invention is not limited to the use of fastenings of that particular character.

Having described the invention, what I claim as new and desire to secure by Letters Patent of the United States is:

1. In a lasting machine, the combination with means for shaping an upper over a last, of means for fastening the upper to a sole on the last comprising devices arranged relatively to each other for alternative use respectively to drive fastenings and to curve them prior to and during their entrance into the shoe to anchor them in the shoe or to lay the marginal portion of the upper over the outer face of the sole and press it into position to adhere to said face in lasting the shoe with cement instead of with driven fastenings.

2. In a lasting machine, the combination with means for shaping an upper over a last, and means for fastening the upper to a sole on the last comprising fastening-inserting mechanism movable inwardly over the bottom of the shoe into upper-fastening position and having means for curving each fastening prior to and during its entrance into the shoe to anchor it in the shoe, of a device mounted for movement into such relation to said fastening-inserting mechanism as to move with said mechanism over the shoe to lay the marginal portion of the upper over the outer face of the sole and to press it upon said face in lasting the shoe without driven fastenings.

3. In a lasting machine, the combination with means for shaping an upper over a last, and means for fastening the upper to a sole on the last comprising a staple guide and a deflector arranged relatively to said guide to curve the legs of the staple prior to and during their entrance into the shoe to anchor them in the shoe, of a device arranged relatively to said guide and deflector for use at the will of the operator to lay the marginal portion of the upper over the outer face of the sole and press it into position to adhere to said face in lasting the shoe with cement instead of with staples.

4. In a lasting machine, the combination with means for shaping an upper over a last,

and means for fastening the upper to a sole on the last comprising a staple guide movable inwardly over the bottom of the shoe into upper-fastening position and a deflector movable with said guide and arranged to curve the legs of the staple prior to and during their entrance into the shoe to anchor them in the shoe, of a device mounted for movement into such relation to said guide and deflector as to move with them over the shoe to lay the marginal portion of the upper over the outer face of the sole and to press it upon said face in lasting the shoe without staples.

5. In a lasting machine, the combination with means for shaping an upper over a last, and means for fastening the upper to a sole on the last comprising a guide for fastenings, a deflector arranged to curve each fastening prior to and during its entrance into the shoe to anchor it in the shoe, and a carrier for moving said guide and deflector inwardly over the bottom of the shoe into upper-fastening position, of a member supported on said carrier and movable relatively thereto into such relation to said guide and deflector as to move with them over the shoe to lay the marginal portion of the upper over the outer face of the sole and press it into position to adhere to said face in lasting the shoe with cement instead of with driven fastenings.

6. In a lasting machine, the combination with means for shaping an upper over a last, and means for fastening the upper to a sole on the last comprising a staple guide and a deflector arranged relatively to said guide to curve the legs of the staple prior to and during their entrance into the shoe to anchor them in the shoe, said guide and deflector being movable inwardly over the bottom of the shoe to engage the marginal portion of the upper and lay it over the sole, of a device mounted for movement at the will of the operator into such a position as to move with said staple guide and deflector over the shoe to engage the upper and lay it over the sole in lasting the shoe with cement instead of with staples, said device being so constructed as to engage the upper over a greater extent lengthwise of the edge of the shoe bottom than said guide and deflector.

7. In a lasting machine, the combination with means for shaping an upper over a last, and fastening-inserting mechanism movable in a direction inclined toward the bottom of the last to lay the marginal portion of the upper over a sole on the last prior to the driving of a fastening through the upper and into the sole, of a device movable at the will of the operator into such a position as to move with said fastening-inserting mechanism in the same direction over the shoe to lay the upper over the sole and press it upon the sole in lasting the shoe with cement instead of with driven fastenings.

8. In a lasting machine the combination

with means for shaping an upper over a last, and means for fastening the upper to a sole on the last comprising a staple guide and a deflector arranged relatively to said guide to curve the legs of the staple prior to and during their entrance into the shoe to anchor them in the shoe, said guide and deflector being movable in a direction inclined toward the bottom of the last to lay the marginal portion of the upper over the sole prior to the driving of the staple, of a device mounted for movement at the will of the operator into such relation to said guide and deflector as to move with them over the shoe in the same inclined direction to lay the upper over the sole and press it upon the sole in lasting the shoe without staples.

9. In a lasting machine, the combination with means for shaping an upper over a last, and means for fastening the upper to a sole on the last comprising fastening-inserting mechanism and a slide for supporting said mechanism and for moving it in a direction inclined toward the bottom of the last to lay the marginal portion of the upper over the sole, of a member supported by said slide to move therewith and movable also relatively to the slide into such relation to said fastening-inserting mechanism as to engage the upper and lay it over the sole in lasting the shoe with cement instead of with driven fastenings.

10. In a lasting machine, the combination with means for shaping an upper over a last, and means for fastening the upper to a sole on the last comprising a guide for fastenings and a carrier for moving said guide inwardly over the bottom of the shoe into upper-fastening position, of a member supported by said carrier and movable either into or out of such relation to said guide as to lay the marginal portion of the upper over the sole by movement with the guide over the shoe bottom, a device supported by said carrier for moving said member into that relation to the guide, and a controlling member supported independently of the carrier and connected to said device for moving it.

11. In a lasting machine, the combination with means for shaping an upper over a last, and means for fastening the upper to a sole on the last comprising a guide for fastenings and a carrier for moving said guide inwardly over the bottom of the shoe into upper-fastening position, of a member supported by said carrier and movable either into or out of such relation to said guide as to lay the marginal portion of the upper over the sole by movement with the guide over the shoe bottom, a cam plate supported by the carrier and mounted for turning movement to move said member into or out of that relation to the guide, and a controlling member supported independently of said carrier and connected to said cam plate for operating it.

12. In a lasting machine, the combination with means for shaping an upper over a last, and means for fastening the upper to a sole on the last comprising a guide for fastenings and a carrier for moving said guide inwardly over the bottom of the shoe into upper-fastening position, of a member supported by said carrier and movable either into a position in such relation to said guide as to lay the marginal portion of the upper over the sole by movement with the guide over the shoe bottom or into an idle position, a spring for holding said member in its idle position, and a cam device supported by the carrier for moving the member to its other position. 5 70
13. In a lasting machine, the combination with means for shaping an upper over a last, and means for fastening the upper to a sole on the last comprising a guide for fastenings and a carrier for moving said guide inwardly over the bottom of the shoe into upper-fastening position, of a member supported by said carrier and movable either into a position in such relation to said guide as to lay the marginal portion of the upper over the sole by movement with the guide over the shoe bottom or into an idle position, and a cam device supported by the carrier for moving the member to its other position. 10 75
14. In a lasting machine, the combination with means for shaping an upper over a last, and means for fastening the upper with staples to a sole on the last comprising stapling mechanism having means for curving the legs of each staple prior to and during their entrance into the shoe to anchor them in the shoe, of a device mounted for movement relatively to said stapling mechanism into position for use to engage the marginal portion of the upper and lay it over the sole in lasting the shoe with cement instead of with staples, and means for preventing the stapling operation when said device is in use. 15 80
15. In a lasting machine, the combination with means for shaping an upper over a last, and means for fastening the upper with staples to a sole on the last comprising stapling mechanism movable inwardly over the bottom of the shoe to lay the marginal portion of the upper over the sole and having means for curving the legs of each staple prior to and during their entrance into the shoe to anchor them in the shoe, of a device movable into such relation to said stapling mechanism as to engage the marginal portion of the upper and lay it over the sole while moving with said mechanism over the shoe bottom in lasting the shoe with cement instead of with staples, and means for preventing the stapling operation when said device is in use. 20 85
16. In a lasting machine, the combination with means for shaping an upper over a last, and means for fastening the upper to a sole on the last comprising a driver for driving fastenings through the upper and into the sole, of a device arranged for use to lay the marginal portion of the upper inwardly over the outer face of the sole into position to adhere to said face in lasting the shoe with cement instead of with driven fastenings, and means for preventing the operative movement of the driver when said device is in use. 25 90
17. In a lasting machine, the combination with means for shaping an upper over a last, means for fastening the upper with staples to a sole on the last, means for forming the staples, and means for feeding wire to said forming means, of a device mounted for movement at the will of the operator into position for use to lay the marginal portion of the upper over the sole in lasting the shoe without staples, and mechanism for rendering the wire-feeding means inoperative when said device is in use. 30 95
18. In a lasting machine, the combination with means for shaping an upper over a last, means for fastening the upper with staples to a sole on the last comprising stapling mechanism movable inwardly over the bottom of the shoe to lay the marginal portion of the upper over the sole, means for forming the staples, and means for feeding wire to said forming means, of a device movable at the will of the operator into such a position in relation to said stapling mechanism as to engage the upper and lay it over the sole while moving with said mechanism over the shoe bottom in lasting the shoe with cement instead of with staples, a member for moving said device into that position, and mechanism controlled by said member for rendering the wire-feeding means inoperative when the device is in that position. 35 100
19. In a lasting machine, the combination with means for shaping an upper over a last, and means for fastening the upper to a sole on the last comprising a driver for driving fastenings through the upper and into the sole, of a device arranged for use to lay the marginal portion of the upper inwardly over the outer face of the sole into position to adhere to said face in lasting the shoe with cement instead of with driven fastenings, and means for preventing the operative movement of the driver when said device is in use. 40 105
20. In a lasting machine, the combination with means for shaping an upper over a last, and means for fastening the upper to a sole on the last comprising a driver for driving 45 110
21. In a lasting machine, the combination with means for shaping an upper over a last, and means for fastening the upper to a sole on the last comprising a driver for driving 50 115
22. In a lasting machine, the combination with means for shaping an upper over a last, and means for fastening the upper to a sole on the last comprising a driver for driving 55 120
23. In a lasting machine, the combination with means for shaping an upper over a last, and means for fastening the upper to a sole on the last comprising a driver for driving 60 125
24. In a lasting machine, the combination with means for shaping an upper over a last, and means for fastening the upper to a sole on the last comprising a driver for driving 65 130
25. In a lasting machine, the combination with means for shaping an upper over a last, and means for fastening the upper to a sole on the last comprising a driver for driving 70 135

fastenings through the upper and into the sole, of a device mounted for movement at the will of the operator into position for use to lay the marginal portion of the upper inwardly over the outer face of the sole in lasting the shoe with cement instead of with driven fastenings, a member for moving the device into that position, and mechanism controlled by said member for preventing the operative movement of the driver when the device is in that position.

21. In a lasting machine, the combination with means for shaping an upper over a last, and means for fastening the upper to a sole on the last comprising a guide for fastenings movable inwardly over the bottom of the shoe to lay the marginal portion of the upper over the sole, and a driver for driving the fastenings, of a device movable at the will of the operator into such relation to said guide as to engage the upper and to lay it over the sole while moving with the guide over the shoe bottom in lasting the shoe without driven fastenings, and mechanism connected to said device for movement into position to prevent the operation of the driver when the device is moved into that relation to the guide.

22. In a lasting machine, the combination with means for shaping an upper over a last, and means for fastening the upper to a sole on the last comprising a guide for fastenings movable inwardly over the bottom of the shoe and a driver for driving the fastenings, of a device movable at the will of the operator into such relation to said guide as to engage the marginal portion of the upper and lay it over the sole while moving with the guide over the shoe bottom in lasting the shoe without driven fastenings, a member for controlling said device, and mechanism controlled by said member for preventing the operative movement of the driver when the device is in that relation to the guide.

23. In a lasting machine, the combination with means for shaping an upper over a last, means for fastening the upper with staples to a sole on the last comprising a staple guide movable inwardly over the bottom of the shoe and a staple driver, means for forming the staples, and means for feeding wire to said forming means, of a device movable at the will of the operator into such relation to said staple guide as to engage the marginal portion of the upper and lay it over the sole while moving with the guide over the shoe bottom in lasting the shoe without staples, a member for controlling said device, and means also controlled by said member for preventing operative movement of the staple driver and also the feeding of wire when the device is in that relation to the staple guide.

24. In a lasting machine, the combination with means for shaping an upper over a last, of upper-fastening means comprising a

guide for fastenings, a carrier for moving said guide inwardly over the shoe bottom, a spring-operated driver, a device for retracting the driver and for tensioning its operating spring by the movement of the carrier, a member supported by the carrier and movable at the will of the operator into such relation to said guide as to engage the marginal portion of the upper and lay it inwardly over the shoe bottom in lasting the shoe without driven fastenings, and means for rendering said device inoperative to retract the driver when said member is in that relation to the guide.

25. In a lasting machine, the combination with means for shaping an upper over a last, of upper-fastening means comprising a guide for fastenings, a carrier for moving said guide inwardly over the shoe bottom, a driver, a spring-operated lever on the carrier for operating the driver, a latch arranged to connect with said lever to swing it against the resistance of its operating spring by the movement of the carrier, a member on the carrier movable at the will of the operator into such relation to said guide as to engage the marginal portion of the upper and lay it inwardly over the shoe bottom in lasting the shoe without driven fastenings, and means for preventing the latch from connecting with said lever when said member is in that relation to the guide.

26. In a lasting machine, the combination with means for shaping an upper over a last, of upper-fastening means comprising a guide for fastenings, a carrier for moving said guide into upper-fastening position, a spring-operated driver, a device for retracting the driver and for tensioning its operating spring by the movement of the carrier, and means adapted for use at the will of the operator to render said device inoperative when the carrier is moved.

27. In a lasting machine, the combination with means for shaping an upper over a last, of upper-fastening means comprising a guide for fastenings, a carrier for moving said guide into upper-fastening position, a spring-operated driver, a latch arranged to retract the driver and to tension its operating spring by the movement of the carrier, and mechanism movable at the will of the operator into position to prevent said latch from acting on the driver and spring when the carrier is moved.

28. In a lasting machine, the combination with means for shaping an upper over a last, of upper-fastening means comprising a guide for fastenings, a carrier for moving said guide into upper-fastening position, a driver, a spring-operated lever on the carrier for operating the driver, a device for swinging said lever against the resistance of its operating spring by the movement of the carrier, and means enabling the operator at

will to prevent said device from acting on the lever when the carrier is moved.

29. In a lasting machine, the combination with means for shaping an upper over a last, of upper-fastening means comprising a guide for fastenings, a carrier for moving said guide into upper-fastening position, a driver, a spring-operated lever on the carrier for operating the driver, a latch arranged to connect with said lever to swing it against the resistance of its operating spring by the movement of the carrier, and a device movable at the will of the operator into position to prevent the latch from connecting with the lever.

30. In a lasting machine, the combination with means for pulling an upper over a last successively in different locations along the side of the last as the shoe is presented by the operator in different positions, a shoe bottom rest and a side gage for controlling the shoe, and upper-fastening mechanism movable inwardly over the bottom of the shoe to lay the marginal portion of the upper over the sole prior to the driving of a fastening through the upper and into the sole, of a device movable at the will of the operator into such relation to said upper-fastening mechanism as to engage the upper and lay it over the sole while moving with said mechanism over the shoe bottom in lasting the shoe without driven fastenings, and means for effecting a change of position of the side gage heightwise of the shoe as said device is moved into that relation to the upper-fastening mechanism.

31. In a lasting machine, the combination with means for pulling an upper over a last successively in different locations along the side of the last as the shoe is presented by the operator in different positions, a shoe bottom rest and a side gage for controlling the shoe, and upper-fastening mechanism movable inwardly over the bottom of the shoe to lay the marginal portion of the upper over the sole prior to the driving of a fastening through the upper and into the sole, of a device movable at the will of the operator into such relation to said upper-fastening mechanism as to engage the upper and lay it over the sole while moving with said mechanism over the shoe bottom in lasting the shoe without driven fastenings, and connections between said device and the side gage for adjusting the side gage heightwise of the shoe when the device is moved into that relation to the fastening mechanism.

32. In a lasting machine, the combination with means for pulling an upper over a last successively in different locations along the side of the last as the shoe is presented by the operator in different positions, a shoe bottom rest and a side gage for controlling the shoe, and upper-fastening mechanism movable inwardly over the bottom of the shoe to

lay the marginal portion of the upper over the sole prior to the driving of a fastening through the upper and into the sole, of a device movable at the will of the operator into such relation to said upper-fastening mechanism as to engage the upper and lay it over the sole while moving with said mechanism over the shoe bottom in lasting the shoe without driven fastenings, a member for moving said device into or out of that relation to the fastening mechanism, and means controlled by said member for effecting an adjustment of the side gage heightwise of the shoe.

33. In a lasting machine, the combination with means for pulling an upper over a last successively in different locations along the side of the last as the shoe is presented by the operator in different positions bottom upward, a shoe bottom rest and a side gage for controlling the shoe, and upper-fastening mechanism movable inwardly over the bottom of the shoe to lay the marginal portion of the upper over the sole prior to the driving of a fastening through the upper and into the sole, of a device movable at the will of the operator into a position under said upper-fastening mechanism to engage the upper and lay it over the sole while moving with said mechanism over the shoe bottom in lasting the shoe without driven fastenings, and means connected to said device for lowering the side gage as the device is moved into that position.

34. In a lasting machine, the combination with means for lasting a shoe successively in different locations along the edge of the shoe bottom as the shoe is presented by the operator in different positions, of a shoe bottom rest and a side gage for controlling the shoe, and a device constructed and arranged to enable the operator to effect a quick change of position of the side gage heightwise of the shoe as the lasting operation progresses from one portion of the shoe to another portion.

35. In a lasting machine, the combination with means for lasting a shoe successively in different locations along the edge of the shoe bottom as the shoe is presented by the operator in different positions, of a shoe bottom rest and a side gage for controlling the shoe, and adjusting means movable lengthwise of the shoe to change the position of the side gage heightwise of the shoe.

36. In a lasting machine, the combination with means for lasting a shoe successively in different locations along the edge of the shoe bottom as the shoe is presented by the operator in different positions, of a shoe bottom rest and a side gage for controlling the shoe, and cam means for adjusting the side gage heightwise of the shoe.

37. In a lasting machine, the combination with means for lasting a shoe successively in

- different locations along the edge of the shoe bottom as the shoe is presented by the operator in different positions, of a shoe bottom rest and a side gage for controlling the shoe, 5 the side gage being mounted for movement heightwise of the shoe, a spring for moving it in one direction, and a cam device cooperating with said spring to vary and determine the position of the gage.
- 10 38. In a lasting machine, the combination with means for pulling an upper over a last successively in different locations along the side of the last as the shoe is presented by the operator in different positions, a shoe bottom rest for controlling the shoe, and upper-fastening mechanism movable inwardly over a sole on the last prior to the driving of a fastening through the upper and into the sole, of an overlaying device movable at the will of the operator into such relation to said upper-fastening mechanism as to engage the upper and lay it over the sole while moving with said mechanism over the shoe bottom in lasting the shoe without driven fastenings, 20 and mechanism constructed to enable the operator to effect a quick adjustment of said shoe bottom rest heightwise of the shoe to position the shoe differently for the use of driven fastenings and for the use of said overlaying device respectively.
39. In a lasting machine, the combination with means for pulling an upper over a last successively in different locations along the side of the last as the shoe is presented by the operator in different positions bottom upward, a shoe bottom rest for controlling the shoe, and upper-fastening mechanism movable inwardly over a sole on the last prior to the driving of a fastening through the upper and into the sole, of an overlaying device movable at the will of the operator into a position under said upper-fastening mechanism to engage the upper and lay it over the sole while moving with said mechanism over the shoe bottom in lasting the shoe without driven fastenings, and mechanism constructed to enable the operator to effect a quick upward or downward movement of said shoe bottom rest in the course of the operation of the machine on the shoe to position the shoe differently for the use of driven fastenings and for the use of said overlaying device respectively.
40. In a lasting machine, the combination with means for lasting a shoe successively in different locations along the edge of the shoe bottom, including mechanism for driving fastenings to fasten the upper to a sole on the last and an overlaying device arranged for alternative use to lay the marginal portion of the upper over the sole in lasting the shoe without driven fastenings, of a shoe rest for engaging the sole to position the shoe for the lasting operations, and mechanism for adjusting said shoe rest heightwise of the

shoe to different automatically determined positions preparatory to the use of driven fastenings and of said overlaying device respectively.

41. In a lasting machine, the combination with means for lasting a shoe successively in different locations along the edge of the shoe bottom as the shoe is presented by the operator in different positions, of a shoe rest for engaging the bottom of the shoe to assist in determining the position of the shoe, said shoe rest being mounted for swinging movement to vary the position of its shoe-engaging portion heightwise of the shoe, and means for holding the shoe rest against such movement throughout a series of lasting operations in different locations along the shoe bottom.

42. In a lasting machine, the combination with means for lasting a shoe successively in different locations along the edge of the shoe bottom as the shoe is presented by the operator in different positions, of a shoe rest for engaging the bottom of the shoe, said shoe rest being mounted for swinging movement to adjust its shoe-engaging portion heightwise of the shoe, a member movable to swing said shoe rest, and means for limiting movements of said member in different directions to determine different adjusted positions of the shoe rest.

43. In a lasting machine, the combination with means for lasting a shoe successively in different locations along the edge of the shoe bottom as the shoe is presented by the operator in different positions, of a shoe rest for engaging the bottom of the shoe, said shoe rest being mounted for swinging movement to adjust its shoe-engaging portion heightwise of the shoe, and an eccentric movable to swing said shoe rest to different positions and arranged to hold it against movement throughout a series of lasting operations in different locations along the shoe bottom.

44. In a lasting machine, the combination with means for lasting a shoe successively in different locations along the edge of the shoe bottom as the shoe is presented by the operator in different positions, of a shoe rest for engaging the bottom of the shoe, said shoe rest being mounted for swinging movement to adjust its shoe-engaging portion heightwise of the shoe, a rotatable member for swinging said shoe rest, means for rotating said member, and mechanism for determining different limits of movement of the member.

45. In a lasting machine, the combination with means for lasting a shoe successively in different locations along the edge of the shoe bottom as the shoe is presented by the operator in different positions, of a shoe rest for engaging the bottom of the shoe, said shoe rest being adjustably movable heightwise of the shoe, a holder supporting the shoe rest

and movable with it, and an eccentric movable by the operator in engagement with said holder to effect a quick adjustment of said shoe rest.

5 46. In a lasting machine, the combination with means for lasting a shoe successively in different locations along the edge of the shoe bottom as the shoe is presented by the operator in different positions, of a shoe rest for 10 engaging the bottom of the shoe, said shoe rest being adjustably movable heightwise of the shoe, an eccentric movable by the operator to effect a quick adjustment of said shoe rest, and means for variably limiting the 15 movement of said eccentric.

47. In a lasting machine, the combination with means for lasting a shoe successively in different locations along the edge of the shoe bottom as the shoe is presented by the operator in different positions, of a shoe rest for 20 engaging the bottom of the shoe, said shoe rest being adjustably movable heightwise of the shoe, a member movable to adjust said shoe rest, and means for variably limiting 25 the movement of said member to determine different adjusted positions of the shoe rest.

In testimony whereof I have signed my name to this specification.

GEORGE GODDU.
